SAFETY PILOT BURNER

James K. Clark, New Hartford, N. Y., assignor to
The Partlow Corporation, New Hartford, N. Y.

Application May 29, 1939, Serial No. 276,475

4 Claims. (Cl. 158—115)

This invention relates to safety pilot burners, more particularly for use with gas-burning furnaces, ovens, and the like, as disclosed in my patent, No. 2,152,790, April 4, 1939.

The primary object of the invention is to provide an improved pilot burner which is of maximum efficiency in affording safety against extinguishment of the flame.

Further, the invention aims to provide a pilot burner wherein the flame from the burner is enveloped by a surrounding flame, which functions to guard or protect the main flame from lifting or being blown away, thus minimizing danger of extinguishment.

Still further, the invention aims to increase the activity of ionization and to improve conduction of the current across the spark gap.

Further, the invention resides in the structure and organization or combination of the parts, as fully hereinafter described and claimed.

In the drawings:

Fig. 1 is a top plan view of the pilot burner, in accordance with one form of the invention.

Fig. 2 is a side elevation.

Fig. 3 is a section on line 3—3 of Fig. 1.

Fig. 4 is a top plan view of another form of the invention.

Fig. 5 is a side elevation, and

Fig. 6 is a section on line 6—6 of Fig. 4.

Fig. 7 is a top plan view of the pilot burner disclosed in my said patent.

Fig. 8 is a side elevation, and

Fig. 9 is a section on line 9—9 of Fig. 7.

In the form of the invention depicted in Figs. 1-3, a hollow body 1, is provided and which is formed with a lateral nipple 2 connected to a branch 3, that in turn is connected to a raw gas source of supply. A porcelain insulator 4 is secured to the body by a nut 5, and is equipped with a metal electrode 6 which projects from its upper end. An insulator 7 of cylindrical form has an outwardly extending flange 8 at its bottom engaged by a ring nut 9 threaded into engagement with the upper end of the body 1, and by virtue of which the insulator is rigidly clamped in position.

The upper end of the insulator 7 is provided with an inwardly extending flange 10, through which extends a sleeve 11 having a flange 12 at its top that overlies the flange 10, and is clamped in position by means of a nut 13, engaging the under face of the flange 10. A metal burner tip 14 is threaded into the outer end of sleeve 11.

A coil spring conductor 15, preferably of bronze, is interposed between the upper end of the por-

celain member 4 and nut 13, and engages the protruding end of electrode 6. The upper portion of the nut 9 slidably receives thereover a ring 16, which has suitably secured thereto a series of substantially inverted L-shaped electrodes 17. The lower ends of the electrodes may be anchored in the ring 16, for example by brazing or welding, as depicted. The upper ends 18 of the electrodes confront one another and overlie the tip 14, being spaced therefrom and radiate from the tip in effect forming substantially a ring of metal thereabout. The ends 18 of the electrodes are preferably equally spaced and due to their described arrangement, afford positive crossing of the spark gap, in operation. The electrode carrying ring 16 by virtue of its vertical sliding movements may accordingly be adjusted to vary the width of the gap, and is fixedly held in selected position by means of a set screw 19.

As illustrated in Figs. 4-6, a body 50, is provided with a porcelain insulator 51, and with an insulator 52 of cylindrical form. The insulator in this instance is formed with a gas burning chamber 53 and an integral burner tip 54', the base of the latter being formed with a series of preferably four gas passages 55 to conduct gas into the chamber 53.

A pair of spaced opposed substantially U-shaped inner electrodes 54, have their arms extending through openings provided therefor in the insulator, and their bases engaged by a coil spring 55', which latter seats on the upper end of porcelain member 51, and engages the electrode 56 of the latter.

The upper ends of the electrodes extend into the gas chamber 53 and surround the gas or burner tip 54', as shown in Fig. 6. A series of outer electrodes 57, of generally inverted L-shape, are rigidly anchored at their lower ends to a vertically adjustable ring 58, the latter being held in adjusted position by means of a set screw 59.

The flame x'' issuing from the chamber 53, envelopes that issuing from the tip of the burner 54', and functions to prevent the flame issuing from the tip from rising or blowing away, which latter objections frequently occur when slow burning gas, such as natural gas, is used with burners of the conventional type. The electrodes 54, are formed of corrosion-resisting alloy, and due to their surrounding the burner tip, contact the outer or enveloping flame, as shown in dotted lines in Fig. 6. With this arrangement ionization is of greater activity and improved conduction of the current across the gap results.

The form of the invention depicted in Figs. 7-9,

is that disclosed in my said patent, and for the sake of clarity in identification, the same reference characters are employed therein, as in the said patent.

Accordingly, a hollow body 30 is provided, and which is formed with an upwardly facing internally and externally threaded nipple 32, a lateral similarly threaded nipple 33 which is supplied with raw gas by the branch 34, and a downwardly facing internally threaded opening 35 in which is disposed a porcelain insulator 36 that protects a metal electrode 37, which extends axially in the porcelain, and whose bottom end is equipped with a binding-post 38. The porcelain 36 is held in place by a gland-nut 39, which threads into the bottom opening of the body 30. In order to further insulate the high tension electrical parts of the pilot burner, an inverted cup-shaped cylindrical lava part 40 whose reduced bottom end is threaded, screws into the nipple 32, which is axial to the porcelain 36. The top end of the electrode member 37 is fitted with a spring 41, which is capped with a washer 42 that frictionally engages the reduced lower end of a threaded metal conductor or terminal 43, having an axial gas passage or orifice 44, which forms one side of the spark gap x. This produces a continuous sole and free passage for the gas delivered by the branch 34. The spark gap x is then completed by the top end 43' of the terminal 43 and a plurality of equally spaced metal electrodes 45, which are anchored in a threaded collar or nut 46 that screws onto the nipple 32. The upper ends of the electrodes 45 are preferably equally spaced and bent inwardly radially so as to facilitate the certain crossing of the gap as the various exigencies of the pilot burner arise.

By the provision of the relatively large number of the electrodes 45 and the regular spacings of their free tips, a ring of metal is formed that aligns axially with the terminal 43, and the other insulating supports render failure of the pilot burner practically impossible.

In each instance, the gas supply pipe is ground-

ed and the electrode 6, 51, and 36 connected in the line 15', as disclosed in my said patent, and as indicated in Figs. 3, 6, and 9 of the instant application.

What is claimed is:

1. A pilot burner, including a body having an insulated electrode therein, said body having an insulator member therein formed with a gas chamber disposed above the electrode and having a burner, and further having gas passages for conducting gas into the chamber, a series of inner electrodes in the chamber surrounding the burner, means to electrically connect the first named electrode to the inner series of electrodes, and an outer series of electrodes surrounding the first named series and having free ends confronting each other and disposed above the first named series with their free ends forming a ring-like arrangement.

2. A pilot burner in accordance with claim 1, wherein the inner electrodes are arranged in pairs, each pair being integrally formed and of U-shape having their arms extending through openings provided therefor in the insulator member, and wherein the means to connect the first named electrode to the inner series of electrodes consists of a coil spring disposed between the first named electrode and the inner series of electrodes and which bears against the bases of the U-shaped pairs.

3. A pilot burner including a body formed with a gas outlet and a gas chamber surrounding the outlet, means to supply gas to the outlet and to the chamber, a series of inner electrodes in the chamber surrounding the outlet, an outer series of electrodes surrounding the first named series, and means to electrically connect the electrodes to produce spark gaps.

4. A pilot burner in accordance with claim 3 where in the electrodes of the outer series have free ends located above the gas chamber and above the electrodes of the inner series.

JAMES K. CLARK.
